UNITED STATES PATENT OFFICE.

BERTHOLD WOLFF, OF OFFENBACH-ON-THE-MAIN, GERMANY, ASSIGNOR OF ONE-HALF TO THE FIRM OF G. BOCHOW, GESELLSCHAFT MIT BESCHRÄNKTER HAFTUNG.

COMBINED VAPOR AND LIQUID ACTUATED ENGINE.

1,095,974.

Specification of Letters Patent.

Patented May 5, 1914.

Application filed December 13, 1913. Serial No. 806,602.

To all whom it may concern:

Be it known that I, BERTHOLD WOLFF, a citizen of the German Empire, residing at Offenbach-on-the-Main, in Germany, have invented certain new and useful Improvements in Combined, Vapor and Liquid Actuated Engines, of which the following is a specification.

The object of this invention is to provide an improved method of, and means for, actuating an engine by means of a liquid of low boiling point, such as carbon dioxid. To this end I use a constant quantity of such liquid, which I alternately heat and condense, and arrange to act on a liquid, such as mercury, the circulation of which, controlled by suitable valve gear, actuates the engine.

An embodiment of the invention is shown in the accompanying drawing in vertical section.

In the drawing, *a* designates a container, in which there is a body of mercury *b*, with a layer of liquid carbon dioxid *c* thereon. A valve *d* in the lower part of the container is connected by a pipe *e* to a turbine *f* in a casing *r*. Instead of the turbine a rotary piston engine may be used. The casing *r* has a downward extension *s*, and by opening a valve *t* this extension *s* may be placed in communication with an explosion chamber *n* suspended within the container *a*. An automatic valve *o* opens from the chamber *n* to the interior of the container *a*. The turbine is mounted on a shaft *u* which controls the valves *d* and *t* by means of suitable connections *q* and *2*.

The turbine actuates an air compressor *k*, which forces air into a container *v*. The latter is connected by a pipe *l* to the housing of a valve *m* opening into the chamber *n* and is also connected by a pipe *x* to a cooling jacket *p* around the upper part of the container *a*, the pipe *x* being controlled by a valve *y*. The valve *m* is opened at intervals by means of valve gear *m'* actuated by the shaft *u*, and the valve *y* is alternately opened and closed by means of gear *y'* actuated by the same shaft. The chamber *n* has an exhaust valve *3*, controlled by valve gear *3'* from the shaft *u*. A pipe *l'* supplying gaseous fuel is connected to the housing of the valve *m*.

The action of the apparatus is as follows:—The turbine is actuated by mercury

forced through the pipe *e*, as will be described hereinafter. From the turbine the mercury drops into the casing *r* and flows into the extension *s*. The shaft *u* then temporarily opens the valve *t* by means of the gear *2*, and the mercury enters the chamber *n*, the valve *t* being closed again. The valve *m* is then temporarily opened, and admits a mixture of air and combustible gas to the chamber *n*, whereupon the said mixture is exploded, and forces the mercury through the orifice controlled by the valve *o* into the container *a*. The explosion is produced by the heat of the compressed air, but a sparking plug or equivalent appliance may be used. The heat of the explosion partly evaporates the carbon dioxid *c*, and the pressure due to the explosion and to this evaporation forces mercury from the container *a* through the pipe *e* to the turbine, the valve *d* being opened by the engine for this purpose. The evaporation of the carbon dioxid is partly due to contact with the hot explosion chamber, and partly due to the forcing of the mercury in a finely divided state into the container *a*. The carbon dioxid is liquefied again by the cooling jacket *p*, to which air from the compressor is supplied at intervals, with expansion accompanied by great reduction of temperature. The mercury in the container *a* is also kept cool by the jacket.

What I claim as my invention and desire to secure by Letters Patent of the United States is:

1. In combination a liquid-actuated engine, a container adapted to hold a body of actuating liquid and a layer of liquid of different specific weight, an explosion chamber within said container, means for supplying actuating liquid from said container to the engine, said supply means including a valve controlled by the engine, means for admitting spent actuating liquid from the engine to said explosion chamber, including a valve controlled by the engine, means for an automatic valve opening under pressure from said explosion chamber to said container, for the purpose set forth.

2. In combination, a liquid-actuated engine, an air compressor actuated by said engine, a container adapted to hold a body of actuating liquid and a layer of liquid of different specific weight, a cooling jacket on said container, an explosion chamber within said container, means including a
